UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

VIBRATION-RESPONSIVE DEVICE.

Application filed April 27, 1923, Serial No. 634,983. Renewed May 3, 1927.

This invention relates to vibration responsive devices.

An object of this invention is to provide a mechanical corrective or attenuating network which may be employed for improving the frequency transmission characteristic of a mechanical vibrating system, for example an acoustic device, such as a telephone transmitter or an electric phonograph reproducer.

10 A second object is to provide an improved lever arm support for a phonograph reproducer or recorder.

A third object is to reduce or modify reflection effects in a carbon button which tend 15 to impair the constant frequency translation characteristic desired.

It has previously been shown in my patent application Serial No. 603,005, filed November 24, 1922, of which this is a continuation in part, that it is possible to build up 20 a mechanical network which may be employed in mechanical vibrating systems for the same purpose for which filters and other corrective networks are employed in electric 25 systems. A mechanical filter may, for example, be made, each section of which comprises a series mass and a shunt elasticity corresponding respectively to the inductance and the reciprocal of the capacity of the 30 standard low pass electric filter of the Campbell type, as disclosed in his U. S. Patent No. 1,227,113 of May 22, 1917.

Such a mechanical filter would have a 35 mid-series characteristic impedance of

$$(1) Z_k = \sqrt{MS} \sqrt{3 - \left(\frac{f}{f_c}\right)^2}$$

and a mid shunt characteristic impedance of

$$(2) Z_{1k} = \sqrt{\frac{MS}{\sqrt{3 - \left(\frac{f}{f_c}\right)^2}}}$$

40 both of which for all frequencies below the cut-off are substantially equal to

$$(3) Z_0 = \sqrt{MS}$$

45 50 which in this specification is called the "nominal" impedance of the filter. The "nominal" impedance is the "nominal" characteristic impedance of the filter, which is the impedance of the filter at the cut-off frequency, and is the "nominal" impedance of the filter.

55 final characteristic impedance" and a cut-off frequency of

$$(4) f_c = \frac{3\sqrt{S}}{\pi M}$$

where Z_0 is the characteristic impedance, M is the mass and S the elasticity per section of the mechanical filter, f_c being the cut-off frequency.

Such a mechanical network is therefore of particular utility in the transfer of mechanical vibratory energy between component parts of a vibration responsive device, such for example, as a telephone receiver or phonograph recorder due to its impedance, for frequencies below the cut-off frequency, being substantially constant over the transmitted frequency band. This is for the reason that the mass and elasticity of a mechanical filter are independent of the frequency and, therefore, the expression for " Z_0 " given above is also independent of the frequency.

The mass and elasticity of the vibrating parts to be coupled by this mechanical filter may also be coordinated with the filter, whereby they may be made substantially equivalent to additional sections of the filter and result in a mechanical transmission line having an impedance constant with frequency over a wide transmission band. This arrangement would therefore take care of the elasticity of the vibrating parts, which unless adjusted to cooperate with the mechanical filter in this special way, would tend to give rise to resonance effects within the frequency range to be transmitted.

One arrangement for terminating the network on the side opposite the point of application of the driving force is to connect the multi-section filter to an impedance equal to the nominal characteristic impedance of a filter of an infinite number of sections, the value of which is obtained by Equation 3 above. Such an impedance in an electric phonograph reproducer might be the mechanical impedance of the carbon granules of the carbon button or in an acoustic phonograph it might be the horn. If such a termination is employed, the carbon chamber should preferably be made of sufficient

depth to prevent vibratory energy impressed on the front of the carbon chamber from being reflected in appreciable amounts from the rear wall back to the mechanical filter, 5 since such a reflection in appreciable quantities would, in general, seriously impair the uniform transmission desired.

The series mass and the shunt elasticity of the coupling network may possess widely 10 different forms and may comprise, for example, a packing between the driving and driven members comprising a plurality of weights separated by resilient means for conveying the motion of one weight to the succeeding weights. The form hereinafter described in detail in connection with the movable parts of the electric phonograph reproducer comprises a plurality of discs enclosed in a suitable casing and separated 20 from each other by a plurality of thin metal foil sheets of a light material, such as aluminum. The mass per section of such mechanical transmission line is, therefore, due principally to the mass of each disc, while 25 the shunt elasticity is due to the combined effect of the thin film of air between adjacent foil sheets and the sheets themselves as the sheets are compressed and separated by the vibratory motion to be transmitted.

Referring to the drawings, Fig. 1 is a representation of an electric low pass filter or lumped loaded transmission line. Fig. 2 is a rearrangement of the elements of Fig. 1 to illustrate satisfactory initial and terminating conditions therefor. Fig. 3 is an electric low pass filter or lumped loaded transmission line, each section of which comprises resistances for attenuating the transmitted frequency band. Fig. 4 is a diagrammatic 40 showing of the relation of the various component parts of an electric phonograph reproducer. Fig. 5 shows how this invention may be embodied to provide a coupling means between driving and driven elements.

Fig. 6 is a sectional view of Fig. 5. Figs. 7 and 8 illustrate this invention embodied in a telephone transmitter. Figs. 9 and 10 illustrate this invention as applied to an electric push-pull phonograph reproducer; 50 Figs. 11 and 12 show modifications of this invention applied to a telephone transmitter and Fig. 13 illustrates the frequency transmission characteristic of the device of Fig. 9.

As is well known in the art, a low pass 55 electric filter usually comprises a plurality of sections, each consisting of a series inductance and a shunt capacity, as illustrated in Fig. 1 by the connections of the series inductances 15, 16, 17 and 18 and shunt capacities 19, 20 and 21. Such a filter as disclosed in the Campbell U. S. Patent No. 1,227,113 of May 22, 1917, may be arranged by equations therein given to provide for the practically free transmission of a given 60 range of frequencies, while almost entirely

suppressing frequencies above that range. In case it would be desired to attenuate appreciably the band of frequencies to be transmitted, each section may be made to comprise, as shown in Fig. 3, a series inductance 70 22, a series resistance 23, a shunt capacity 24 and a shunt inductance 25. Fig. 3, of course, may also be regarded as illustrative of a telephone line, for example, in accordance with the Pupin system in which the inductances 75 22 represent the inductance per section, resistance 23 the resistance of the line per section, capacities 24 the capacity of the line per section and of the shunt resistances 25 the leak across the line or the conductance 80 per section.

The mechanical wave filter which would be analogous to the electric filter of Fig. 1 would, therefore, comprise a plurality of sections, each section comprising a series mass 85 (inductance) and a shunt elasticity (capacity). These masses and elasticities may be assigned such values according to Equations 3 and 4 that the mechanical transmission line will have a definite cut-off frequency while having a substantially constant transmission characteristic for frequencies below the cut-off frequencies. If in addition to the masses and elasticities, frictional or dissipative losses are introduced both effectively in series and in shunt to the line a mechanical system analogous to the electric system of Fig. 3 may be produced which may be employed, for example, as a pure resistance or an artificial line in a vibrating system. When the number of sections per wave length i. e., the number of sections required to give a phase shift of 2π is large such a line is substantially equivalent to a line of distributed constants in which the condition 100 105 that the impedance is substantially a pure resistance is

$$(5) \frac{r}{S} = gM$$

where S is the elasticity per section, M the mass per section, r the series dissipative mechanical resistance and g is the measure of the shunt dissipation in a unit section and corresponds to the shunt conductance in the 115 electrical case.

Fig. 5 illustrates the mechanical equivalent of the electrical transmission line shown diagrammatically in Fig. 3. The mechanical transmission of Fig. 5 comprises a cylindrical casing 30 enclosing a plunger 31 connected to a suitable driving member 32 and a similar plunger 33 connected to a member 34 which is to be driven by vibratory motion from the driving member 32. Located between the plungers 31 and 33 are a plurality of lumped masses comprising discs 35 which are spaced apart by a large number of thin sheets of material light in weight, such as paper or aluminum foil. The plungers 31 130

and 33 serve to close each end of the casing 30 and the result of the movement of the plunger 31, for example, will be a motion transmitted through the air cushioned foil sheets 36 and the spaced weights 35 to the plunger 33 at the opposite end. The spaced weights 35 constitute the masses of a mechanical transmission line and the air included between the thin air cushioned sheets 10 of foil presents an elastic reactance to give the shunt elasticity desired so that Fig. 5 is a mechanical equivalent of the electrical system of Fig. 1 or Fig. 3 depending on the presence or absence of dissipation. The system of Fig. 5 may be employed in a mechanical system with any desired frequency transmission characteristic and may be so constructed with respect to the distributed masses and elasticities as to have a substantially constant impedance for a wide range of frequencies. The chief function of the foil sheets 36 is to provide thin layers of air to give the required elasticities to the line, that is, the elasticity is due to the air 25 confined between the sheets and not due solely to the sheets themselves. If the sheets fit into the casing tightly so as to substantially prevent the escape of the air between the sheets, there is very little dissipation or 30 energy loss and the mechanical line is the substantial equivalent of the electrical line of Fig. 1. If the sheets fit loosely in the casing, the mechanical line will be equivalent to Fig. 3 since both elasticity and dissipation 35 would be present.

In order that a smooth mechanical transmission line may result from the use of such an arrangement as that shown in Fig. 5 it will generally be preferable to design the 40 vibratory elements of which plungers 31 and 33 are component parts to have such series masses and shunt elasticities as to give equivalent additional sections to the mechanical filter. If a mid-shunt termination 45 of a filter is desired, for example, each of the plungers 31 and 33 may be made to have a mass equal to the mass assigned to a section of the filter while the driving and driven members 32 and 34 are assigned 50 elasticities twice the elasticity of each filter section. Other terminating arrangements, of course, may be employed as are well known in the art of electric filters, such as mid-series termination and the like.

Fig. 6 is a cross-sectional view of Fig. 5 and further explanation is believed unnecessary.

Figs. 7 and 8 illustrate a specific application of the mechanical device of Fig. 5 and 60 illustrate the device employed in a telephone transmitter. The telephone diaphragm 40 is coupled by a pin 41 to a carbon button 42, whereby in the manner well known in the art the vibrations of the diaphragm 40 produced by impressed sound waves will vary

the pressure exerted upon the granular material in the chamber 42, thereby varying its resistance to the current flowing therethrough from battery 43. The diaphragm 40, however, usually has a rather pronounced 70 resonance whereby certain frequencies tend to be unduly emphasized by the transmitter. In order to give the transmitter an approximately constant frequency transmission characteristic over a wide range of frequencies, thereby avoiding the resonance of the diaphragm, a plurality of spaced masses 44 are provided between the diaphragm and the side wall 47 of the casing and spaced from each other and from the diaphragm by 75 sheets 45 of thin material, such as aluminum foil. This causes the diaphragm 40 which is the first section of the mechanical line to work into an impedance which is substantially independent of frequency over any desired range. The weights 44 and the sheets 45 may be disc-shaped, for example, with a central aperture to provide for the coupling pin 41. With such a packing arrangement, the response of the diaphragm will depend upon the masses of 80 the discs 44 and the elasticity of the thin films of air confined between the thin sheets 45. By suitably adjusting the elasticity and the dissipation in the masses according to 85 equations above given, the resonance effects of the diaphragm may be substantially overcome so that the transmitter may be employed for faithfully translating into electric waves, sound waves which are impressed 90 on thereon.

It is obvious, of course, that the mechanical line comprising the weights 44 and the foil sheets 45 may be in as many sections as is desired. The casing 48 enclosing the mechanical lines should have such 105 an internal diameter that the weighted discs and the metal foil sheets will slide readily along the inner walls of the casing in response to the plunger action of the diaphragm 40 and will also allow for the escape 110 of the air between the sheets. The discs 44 in general should have a diameter slightly less than the internal diameter of the casing 48. A suitable supporting member 49 is shown for supporting the carbon button 42. 115 The diaphragm 40 may be of any suitable material and either tightly stretched or under very little tension in its position of rest.

Figs. 9 and 10 illustrate this invention 120 embodied in an electric push-pull phonograph reproducer. A hollow casing 50 is disclosed which suitably supports at a plurality of points by means of screws 51 a cylindrical casing 52 internally threaded at each end. 125 A conically shaped member 53 both internally and externally threaded is fitted into each end of the cylindrical casing 52. An externally threaded and flanged metallic ring 54 serves to hold an annular ring 55 of 130

insulating material tightly against the face of a metallic member 56 insulatingly supported from the conical-shaped member 53 by a screw 57. This member 56 has a hemispherical depression in its face to provide a carbon chamber. The carbon chamber is closed by a sheet 58 of flexible insulating material, such as mica for example, which is held away from the flange of the sleeve 54 by a plurality of thin angular rings 59 of material light in weight such as aluminum foil for example.

Located between the apertured cap 60 for the sleeve 54 and the mica sheet 58 is a mechanical transmission line constructed in accordance with this invention. The transmission line comprises a plurality of spaced hat-shaped weights 61 which are separated from each other as well as from the cap 60 and the mica sheet 58 by a plurality of thin annular rings 62 of material such as aluminum foil. Located between the two outside weights of the two parts of the reproducer is the upper end of the pivoted lever arm 65, in the other end of which is fastened a needle 66 which may be employed to traverse a suitable sound record whereby the mechanical vibrations of the lever arm 65 resulting therefrom will vary the pressure exerted upon the carbon granules through the intermediary of the vibrations of the masses 61.

The novel manner in which the lever arm 65 is mounted should be noted. Projecting from a flattened portion or continuation of the casing 52 are two knife edges 96 and 97 located on opposite sides of the opening in the casing through which the arm 65 projects. Suitably fastened to the lever arm 65 is a flat cross piece 98 which in one face has two depressions in which the knife edges 96 and 97 rest while the opposite face is in contact with two knife edges 99 and 100 which are suitably supported from the casing 52. The metallic cross piece 98 should be flexible and elastic so that it may be sprung into place between the knife edges to provide a delicate pivot for the needle arm. All four knife edges should preferably be in line.

The carbon button disclosed is of the barrier type as described and claimed in the U. S. Patent to C. R. Moore, No. 1,583,416, May 4, 1926. The front electrode of the button is the ring 54 while the back electrode is the conical member 56. The annular ring 55 of insulating material constitutes the barrier.

The method of assembly of the apparatus of Fig. 9 will now be explained. First, each carbon button is assembled by placing in the front part of the button the various washers and weights shown after which the cap 60 is threaded on. The lever arm is positioned within the casing 52 and held in place by

the four knife edges 96, 97, 99 and 100. Each carbon button is then screwed into one end of the casing 52 until the outer dome 61 and dome 102 contact with the desired pressure against the upper end of the lever arm 65. This pressure may be checked by measuring the deflection of the needle arm per unit force. It has been found unnecessary to attach the lever arm 65 rigidly to the masses 102 and 61 since the elastic contact pressure alone is sufficient to maintain an efficient mechanical coupling between the lever arm and the reproducing elements. The fact that no permanent fastening means is required makes the assembly of the apparatus a comparatively simple and easy process.

As an example of the type of mechanical transmission line which may be employed between the lever 65 and the carbon chamber, the following illustrative values are given:

In one specific embodiment the weights 61 were .6 inches in diameter and each weighed .07 grams. The annular rings or elastic material between adjacent weights were made of aluminum foil having an external diameter of .8 inches and a thickness of .001 inches. Three sheets were employed between cap 60 and adjacent weights while between the mica sheet 58 and the adjacent weight five sheets were employed. The internal diameter of the cylindrical ring 54 was .85 inches. This was found to give a mass per section of .07 grams and an elasticity per section of $.5 \times 10^8$ dynes per cm. which resulted in a mechanical transmission line having a substantially constant frequency characteristic over the bands of frequencies from 100 cycles to 5,000 cycles per section as shown in the curve 70 of Fig. 13 which is obtained by plotting frequency values as abscissæ with the corresponding power output as ordinates. This curve 70 is shown plotted on a logarithmic scale for the reason that when so plotted octaves along the horizontal axis are represented by equal distances. For example, the distance between 200 cycles and 400 cycles is the same as between 2500 cycles and 5000 cycles, and that is the manner in which the ear hears, by octaves.

The carbon chamber with a radius of .30 inches was found to be sufficient to provide an impedance substantially equal to the impedance of an infinite number of sections of the mechanical line, and also of sufficient length between mica sheet 58 and the back wall to avoid any substantial reflection effects which would tend to impair the uniform frequency transmission characteristic desired. This depth of the carbon chamber is considerably greater than is necessary for merely a carbon transmitter operation since only the carbon particles close to the elec-

trode 54 and the barrier 55 are actually employed in carrying the electric current. The remainder of the carbon is added to give a mechanical impedance equal to the nominal 5 characteristic impedance of the mechanical transmission line in front of the carbon chamber. The impedance presented by the carbon chamber is substantially proportional to the cross sectional area of the carbon 10 chamber and also increases somewhat with increase in depth.

The termination of the carbon button in an impedance of the above character does not require that the impedance be due to 15 additional carbon granules since any other suitable material may be employed to provide the desired impedance termination. The feature of importance is to have the active carbon granules working into some 20 absorbent material capable of absorbing the vibratory motion to an extent sufficient to prevent reflection losses while presenting the desired impedance.

This mechanical termination of a carbon 25 button in an impedance equal to the mechanical impedance as seen from the front of the button is of importance in other types of acoustic devices besides the phonograph reproducer, just described. For example, it 30 may be employed in a telephone transmitter as shown in Fig. 11. A carbon button transmitter is disclosed having a carbon chamber comprising a front electrode 105 and a back electrode 106. This back electrode should be 35 of flexible material such as a wire mesh or gold plated cloth for example to allow the vibrations to be transmitted to that part of the carbon chamber behind electrode 106. It has been found that the best quality of 40 reproduction of the mechanical vibrations of the front electrode 105 takes place when only a thin layer of carbon is located between the electrodes. Preferably the distance between 45 electrodes 105 and 106 should be not greater than 40 mils. A distance between electrodes considerably in excess of 40 mils will frequently impair the quality due to imperfect modulation in the layers of the carbon remote from the front electrode.

The deep carbon chamber disclosed may be 50 employed for providing mechanical means on the side of the active carbon granules opposite the diaphragm for preventing the 55 reflection effects caused in shallow carbon chambers by the elastic reaction of the chamber causing a reflection effect from the back wall of the chamber which varies with the frequency. The cross sectional area and the 60 depth of the carbon chamber may also be adjusted to have a mechanical impedance equal to the mechanical impedance of the moving parts of the transmitter as seen from the front of the carbon chamber.

65 Fig. 12 is a modification of Fig. 11 in which the inactive part of the granular ma-

terial of the carbon chamber has been replaced by other means for providing the desired impedance. Members 115 and 116 constitute the electrodes. The particular means disclosed comprises a plurality of sections of 70 the mechanical transmission line illustrated in Fig. 9, each section comprising a plurality of thin sheets of aluminum foil and a lumped 75 mass. These foil sheets 110 and masses 111 should provide a mechanical line having a 75 surge impedance equal to the surge impedance of the mechanical line in front of the carbon chamber. With such an arrangement the impedance seen in either direction from the active carbon granules will be the same. The particular transmission line shown in 80 Fig. 12 in front of the carbon chamber comprises a diaphragm 112 held between a packing of thin washers 113 and also comprises the mechanical impedance of the long 85 mouth-piece 114 as seen from the smaller end. The number of sections on a mechanical transmission line employed behind the carbon chamber should be sufficient to prevent any appreciable amount of vibratory 90 energy from traversing the length of the mechanical transmission line and being reflected back to the carbon chamber so as to produce the undesired reflection effects 95 mentioned above.

The equivalent circuit diagram for one-half of the phonograph reproducer of 100 Fig. 9 is shown in Fig. 4, in which the capacity or elasticity 71 represents the elasticity of the needle point 66, inductance or mass 72 represents the mass of the lever 65, capacity or elasticity 73 represents the elasticity of the lever arm 65 which in most designs can be disregarded, capacity or elasticity 74 represents the elasticity of the flexible top end 105 of the lever 65, inductances or masses 75 each represent the mass of one of the members 61, while the dissipation due to the motion of the weight relative to the side walls (friction) is designated by the series mechanical resistances 76. The shunt capacity 77 represents the capacity or elasticity due to the 110 enclosed films of air between the sheets 62, and between the masses 61, while the resistance 78 represents the amount of dissipation 115 produced as the air flows from the pockets between the sheets 62 and masses 61. This elasticity 77 may be due principally to the films of air between the sheets 62 or may be due principally to the air pockets between the central portions of the masses 61 as may be desired in any particular case. The capacity or elasticity 79 represents the elasticity of the sheets caused by the sheets being 120 in contact with each other at certain points. The resistance 80 represents the mechanical impedance of the carbon and as mentioned above, impedance 80 should be substantially 125 equal to the impedance of an infinite number of the sections of the mechanical line, that is, 130

they should have a value approximating that given by Equation 3 above. The washers 59 which seal the carbon chamber also act as a series elasticity 95 to furnish a force which holds the hats 61 in engagement with the needle arm 65. This elasticity 95 should be made small in order not to reduce the low frequency output of the reproducer.

By comparison of Figs. 3 and 4 it will be seen that Fig. 4 departs from the ideal case in having part of the shunt elasticity in series with the conductance and part in shunt instead of all in shunt, as shown in Fig. 3. Since Equation 5 above holds only when all of the elasticity is in shunt to the conductance, the ratio of the elasticity 77 to the elasticity 79 should be made as large as possible and therefore insure that the network more nearly approximates the condition covered by Equation 5.

Electrical networks such as that shown in Fig. 1, for example, may be terminated at each end in a variety of ways, the impedance of the arrangement depending upon the manner of its termination. Two common terminations are the mid-series type and the mid-shunt type. In the mid-series type, the end series inductances have values equal to one-half of the value of the inductance for a full section and in the mid-shunt termination, the capacity has a value one half the capacity of that of a full section. The mechanical arrangement of Fig. 9 may be made to have a mid-shunt termination, for example, at the needle end by having the elasticity 71 twice the elasticity of the full section, that is, elasticity 71 would have a value twice the elasticity of element 74 or 77, in those cases in which the elasticity 73 may be disregarded. In other cases the elasticity 71 should have a value only approximately one half of that of the elements 77 so as to give the terminating section the same impedance as the other sections. The termination at the carbon chamber end need not be made special, since the impedance of the carbon chamber represents the impedance of an infinite number of sections. A ready explanation of the manner in which the network should be terminated is shown in Fig. 2, where both the series and the shunt elements are split into two parts. The inductance of a full section comprises the sum of elements 81 and 82, while the total capacity for a single section comprises the sum of the capacities 83 and 84. If the network is terminated at the points 86, the inductance 81 is mated with the capacity 85 which is the same value as either capacity 83 or 84. Inductance 82 is mated with capacity 83. Inductance 87 is mated with capacity 84 and inductance 88 is mated with capacity 89, all of the inductances shown being of equal value and all of the capacities shown being of equal value.

Such a filter can also be terminated at the points 90 and 91, inductance 81 and capacity 85 being omitted, or the network can be terminated at the points 92 and 93, inductances 81 and 82 and capacities 85 and 83 being omitted.

It is to be understood that this invention is not limited to the particular forms that have been described in detail above, since they may be variously modified without departing in any wise from the spirit of the invention as defined in the appended claims.

The invention claimed is:

1. A phonograph reproducer, comprising a carbon button, a flexible closure therefor, a lever arm arranged to be vibrated in accordance with speech frequency vibrations occurring on a sound record, a mechanical transmission line between said lever and said closure comprising a plurality of spaced weights separated by a loose packing of air-cushioned material, said carbon chamber being of sufficient depth to avoid appreciable reflection losses from the wall of said chamber opposite said closure back to said closure.

2. An electric device comprising electrodes, conductive granular material packed between said electrodes, means comprising a flexible member contacting with said material for subjecting said material to mechanical vibrations, and means cooperating with said granular material for causing said granular material to work into a mechanical impedance on that side of said material opposite said flexible member having an impedance of the same order of magnitude as the impedance of said means which subjects said material to mechanical vibrations.

3. An electric device comprising electrodes, a chamber substantially filled with carbon granular material, means for causing an electric current to flow through said granular material, and a flexible member included as one side of said chamber, said chamber being of sufficient depth that the carbon material adjacent the back wall of said chamber is substantially unaffected by the mechanical vibrations of said flexible member.

4. An electric device comprising a chamber substantially filled with carbon granular material, a flexible member acting as one side of said chamber, means for impressing mechanical vibrations of signaling frequencies upon said member, means for supplying an electric current to a portion of said granular material, the mass of said carbon in said chamber being of sufficient depth and cross section as to cause the active carbon material to work into an impedance of the same order of magnitude as the impedance of the said means for impressing mechanical vibrations upon said granular material.

5. An electric device comprising electrodes, conductive granular material packed between said electrodes, means comprising a flexible member contacting with said material for subjecting said material to mechanical vibrations, and means for absorbing the mechanical vibrations of the active granular material, such that the impedance looking in either direction from the active granular material is of the same order of 10 magnitude.
- In witness whereof, I hereunto subscribe my name this 26th day of April, A D., 1923.

HENRY C. HARRISON.
